(57) CLAIM

The ornamental design for a textile pattern, as shown and described.

DESCRIPTION

The file of this patent contains at least one drawing executed in color. Copies of this patent with a color drawing will be provided by the Patent and Trademark Office upon request and payment of the necessary fee.

The sole FIGURE is a plan view of a textile pattern showing my new design it being understood that the serrated borders represent the boundaries of the claimed pattern as well as the boundaries of the textile to which the pattern is applied.
